UNITED STATES PATENT OFFICE.

FREDERICK A. RUGEN, OF BROOKLYN, NEW YORK, ASSIGNOR TO THE
HARTFORD CARPET COMPANY, OF HARTFORD, CONNECTICUT.

DESIGN FOR A CARPET.

SPECIFICATION forming part of Design No. 17,450, dated July 12, 1887.

Application filed June 18, 1887. Serial No. 241,803. Term of patent $\frac{3}{4}$ years.

To all whom it may concern:

Be it known that I, FREDERICK A. RUGEN, of Brooklyn, in the county of Kings and State of New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view 15 of a carpet showing my new design.

My design consists, mainly, of groups of

flowers and leaves irregularly massed and intertwined with certain scroll-like forms occurring at odd intervals among the flowers and leaves. Connected with the scroll-work and scattered without apparent order over the face of the design are varying masses of small ornamental work of a geometrical character. Any suitable ground may be employed.

What I claim as new, and desire to secure by Letters Patent, is—

The design for carpets, consisting of the design substantially as shown.

FREDERICK A. RUGEN.
